UNITED STATES PATENT OFFICE.

DAVID O'NEILL, OF WOODSIDE, NEW YORK.

ROLLING WINDOW-SCREEN.

1,240,768.

Specification of Letters Patent. Patented Sept. 18, 1917.

Application filed November 28, 1916. Serial No. 133,865.

To all whom it may concern:

Be it known that I, DAVID O'NEILL, a citizen of the United States, residing at Woodside, in the county of Queens and State of New York, have invented certain new and useful Improvements in Rolling Window Screens; and I do hereby declare the following to be a full, clear, and exact description of the invention, such as will enable others skilled in the art to which it appertains to make and use the same.

This invention relates to a rolling window screen and has for one of its objects the provision of a device of this character adapted to automatically operate upon opening and closing of a window so that the space caused by the window being in an open position will be closed by the screen and when the window is in a closed position, the screen is rolled up and protected from the weather and other foreign matter.

Another object of this invention is to provide a casing secured to a window frame and having a spring rewound roller therein which is connected to a window sash for closing or cleaning a window when the sash is moved in an open position, thus preventing insects and the like from passing through the window.

A further object of this invention is to provide means for detachably securing one end of the screen to the window sash for causing the screen to move upwardly and downwardly with the sash and which is adapted to close the opening in the casing which permits the screen to enter and exit therefrom when the sash is in a closed position, thus preventing rain and other foreign matter entering the casing.

A further object of this invention is to provide vertical guide members to each end of the casing for receiving and guiding the edges of the screen and which has means thereon for clamping them and the casing to the window frame so that the casing and guide members may be readily detached from the window frame when desired.

A still further object of this invention is the provision of a rolling window screen of the above stated character, which shall be simple, durable and efficient, and which may be manufactured and sold at a comparatively low cost.

With these and other objects in view as it will become more apparent as the description proceeds, the invention consists in cer-

tain novel features of construction, combination and arrangement of parts as will be hereinafter more fully described and claimed.

For a complete understanding of my invention, reference is to be had to the following description and accompanying drawings, in which:

Figure 1 is a front elevation of a window illustrating a rolling window screen applied thereto and which is constructed in accordance with my invention,

Fig. 2 is a vertical sectional view of the same,

Fig. 3 is a fragmentary vertical sectional view illustrating the means of connecting the guide strips to the casing,

Fig. 4 is a longitudinal sectional view of the casing illustrating a spring rewound roller therein,

Fig. 5 is a fragmentary elevation partly in section of the casing illustrating the opening and one of the guide strips for the screen,

Fig. 6 is a detail sectional view taken on the line 6—6 of Fig. 4,

Fig. 7 is a detail elevation of a modified form of securing the guide strips to a window frame.

Referring in detail to the drawings, the numeral 1 indicates a window frame having the usual sill 2 and the vertical guide ways 3 and 4 in which are slidably mounted the upper and lower window sashes 5 and 6. The foregoing description relates to a well known construction of a window and to which my invention is applied. My invention may be readily applied to either the upper or lower window sashes 5 and 6, but to better illustrate the same I have elected to show my invention attached to the lower window sash 6.

An elongated casing 7 is provided with a curved top wall 8 which is slotted adjacent the rear wall thereof as illustrated at 9 for forming an exit or opening to the casing. The casing 7 has its ends closed by end walls 10 which are each apertured for the purpose of rotatably supporting a roller 11, which will be hereinafter more fully described.

A pair of vertically extending guide strips 12 rest on each end of the casing 7 adjacent the slot 9 for receiving the edges of a screen 13 which is wound upon the roller 11 within the casing and extends out

of the casing by way of the slot 9. The 5 guide strips 12 are of substantially U-shape in cross section and have formed thereon right angled flanges 14 to which are pivoted locking arms 15 having cam faces 16. When applying the casing and the guide strips 12 to the window frame 1, the casing 7 is positioned upon the window sill 2 allowing the 10 guide strips 12 to extend vertically in the guide way 3 and by swinging the locking arms 15 into an engagement with one of the walls of the guide way 8 will force the 15 guide strips against the other wall, thus locking the guide strips within the guide way 3 and simultaneously holding the casing 7 upon the window sill 2.

The roller 11 has inserted in the ends thereof cylindrical blocks 17 and 18. The 20 cylindrical block 17 is provided with a circular bore for receiving a pintle 19 that extends through one of the end walls 10 of the casing for rotatably supporting the roller 11. The cylindrical block 18 has a circular bore to receive a pintle 20 which is 25 rotatably mounted in the opening of the other end wall 10 of the casing and has a squared bore 21 for receiving a key for rotating the block 18 within the roller 11. The block 17 is secured to the roller 11 by a 30 screw 22 or like fastener. Each of the blocks 17 and 18 have inwardly directed reduced extensions 23 formed thereon for receiving the ends of a coil spring 24. The 35 ends of the coil spring 24 are secured to the blocks 17 and 18 as illustrated at 25. By rotating a key (not shown) after being positioned within the squared bore 21 of the pintle 20, the block 18 will be rotated thus winding up the spring 24 within the roller 40 so as to cause the roller 11 to wind the screen 13 thereon when released or allowed to move in the direction of the casing 7. The block 18 is provided with an aperture for receiving a pin 26 which is adapted to extend 45 through an aperture in one of the end walls 10 of the casing 7 for locking the block 18 against rotation in the roller 11 after the spring 24 has been wound.

An attaching strip 27 is provided with a 50 longitudinal groove for receiving the free end of the screen 13 and which is secured within the groove by means of pins or like fasteners 28. Downwardly depending tongues 29 are formed on the attaching strip 27 and engage the window sash and are held thereon by substantially U-shaped clamps 30, thus it will be seen when the 55 window sash is moved upwardly and downwardly the window screen 13 is compelled to travel therewith within the guide strips 12. When the window sash is moved in the direction of a closed position, the screen 13 moves downwardly or winds upon the roller 11 within the casing 7 under the influence 60 of the spring 24, so that the screen is en-

tirely incased or inclosed when the window sash is in a closed position.

From the foregoing description taken in connection with the accompanying drawings it will be noted that a screen has been 70 provided which may be readily attached or applied to a window frame and window sash without the use of nails or like fasteners, thus obviating the danger of marring or injuring the wood work of the window 75 frame. It will also be noted that whenever the window sash is moved to an open position so as to allow ventilation of the room, the opening within the window is immediately or automatically closed by the screen 80 13 and immediately upon downward movement of the window sash to a closed position, the screen 13 is wound upon the roller 11 within the casing 7 thus entirely protecting the same from foreign matter when 85 in non-use. It will also be noted that this device may be readily detached from a window frame and sash by removing the clamps 30 freeing the attaching strip 27 from the window sash and turning the locking arms 90 15 upon their pivots so that the guide strips may be detached from the guide ways of the window frame, the casing 7 is then free to be lifted from the window sill 2 and stored in a comparatively small space. 95

Formed upon the attaching strip 27 is an extension 31 which is adapted to overlie the opening 9 of the casing 7 when the window sash is in closed position, thus preventing rain and other foreign matter from entering 100 the casing which would cause the screen 13 to become rusted or injured so as to render it of non-use. The flanges 14 of the guide strips 12 have their lower ends bent at right angles and rest on the casing 7 while 105 the rear wall of the guide strips extend downwardly in rear of the casing, whereby the guide strips are substantially secured to the casing when in operation.

Referring to my modified form of fastening means for the guide strips to the window frame as illustrated in Fig. 7, it consists of an internally screwthreaded boxing 110 33 which is riveted or otherwise secured to the right angled flanges 14 and has threaded 115 therein a rod 34 on which is mounted an actuated nut 35, whereby upon actuating or rotating the nut 35, the rod 34 will be rotated to move said rod into an engagement with one of the walls of the guide ways so 120 as to cause the guide strips 12 to engage the other wall of the guide ways thus efficiently securing them therein.

While I have shown and described the preferred embodiment of my invention, it 125 will be understood that minor changes in construction, combination and arrangement of parts may be made without departing from the spirit and scope of the invention as claimed. 130

Having thus described my invention, what I claim is:

1. A rolling window screen comprising a casing, a spring roller journaled in said casing, a screen wound on said roller and extending exteriorly of the casing, an attaching strip having a groove to receive the free end of the screen, means for securing the screen within the groove, downwardly depending tongues formed on the attaching strip, and substantially U-shaped clamps securing the tongues to a window sash.
2. A rolling window screen comprising a casing, a spring roller journaled in said casing, a screen wound on said roller and extending exteriorly of the casing, means for securing the free end of the screen to a window sash, substantially U-shaped guide strips in cross section secured to each end of the casing and in vertical alinement with the opening in the casing to receive the edges of the screen, and a locking arm pivoted to the guide strips for locking said guide strips to a window frame.
3. A rolling window screen comprising a casing having an elongated slot therein, a roller journaled in said casing, a screen wound on said roller and extending through the opening, means for detachably securing

the free end of the screen to a window sash, 30 vertical guide strips located each end of the elongated slot of the casing to receive the edges of the screen, right angled flanges formed on said guide strips and having their lower ends extended at right angles and secured to the casing, and locking arms pivoted to the flanges for securing the guide strips to a window frame.

4. The combination with a window frame including a sliding sash, a casing carried by 40 the window frame and having an elongated opening, a spring rewound roller journaled in said casing, a screen carried by said roller, means for connecting the screen to the window sash for movement therewith, substantially 45 U-shaped in cross section guides secured to the frame and adapted to receive the edges of the screen, said substantially U-shaped guides having their lower ends spread to engage the top and rear walls of 50 the casing for establishing a connection between the guides and the casing.

In testimony whereof I affix my signature in presence of two witnesses.

DAVID O'NEILL.
